UNITED STATES PATENT OFFICE.

PHILIP J. DAUERNHEIM, OF ST. LOUIS, MISSOURI.

LIME-KILN.

1,240,950.

Specification of Letters Patent. Patented Sept. 25, 1917.

Application filed June 21, 1915. Serial No. 35,896.

To all whom it may concern:

Be it known that I, PHILIP J. DAUERNHEIM, a citizen of the United States, and resident of St. Louis, Missouri, have invented certain new and useful Improvements in Lime-Kilns, of which the following is a specification containing a full, clear, and exact description, reference being had to the accompanying drawings, forming a part 10 hereof.

My invention relates to improvements in lime kilns, and is especially directed to the construction of an internal furnace for a "stack" kiln.

Such internal furnaces are usually constructed of fire brick or other refractory material, best adapted to such use by reason of their qualities to absorb a minimum of heat units and thus afford a maximum of burned lime rock to a given amount of fuel. However, such materials, due to the intensity of heat involved, are of relatively short life, and it is the object of my improvements to combine with an internal furnace constructed of fire brick or analogous material a water cooling system which renders the material of the furnace more capable of withstanding the intense heat, to the end that the furnace is given additional life and is less subject to the need of repair. In the arrangement of the various parts of the cooling system in the internal furnace, my first consideration has been the protection of the furnace against the heat, but, of course, hot water and some steam are made and these may be drawn off as desired, the steam directed to aiding the combustion of the fuel used, or to other purposes, and the hot water directed to its common usages.

With the above and other objects in view, my invention consists in certain novel features of the construction and arrangement of parts, hereinafter fully set forth, pointed out in my claims and illustrated by the accompanying drawings, in which:

Figure 1 is a sectional elevation shewing a water cooling system in an internal furnace installed in a stack kiln, according to my invention;

Fig. 2 is a view similar to Fig. 1, and is taken at right angles thereto;

Fig. 3 is a fragmentary elevation of the kiln embracing that portion containing the furnace and my improved water cooling system therefor; and

Fig. 4 is a sectional plan taken on the line 4—4 of Fig. 3.

In this specification and upon the drawings like reference numerals are employed to designate the various parts and 5 designates the base of the kiln structure, which has formed therein the lime cooling and drawing chamber 6, beneath which chamber 6 the structure is arched for the purpose of forming a passageway 7 beneath the chamber 6 for wagons, trucks and the like, which may be filled directly from the chamber 6. The bottom of the chamber is provided with suitable easily operated closures, such as shown at 8 in the drawings.

The middle upper portion of the chamber 6 is bridged by an arch 9, which is of less width than the chamber, so that the chamber, at its sides, may communicate with the stack 10 above the cooler chamber 6.

Extended through the arch and having their ends seated in the walls of the stack are the I-beams 11, upon which and the arch 9 is supported the internal furnace, whose ends are formed by the walls of the stack 80 and whose sides are formed by the walls 12 built up from the arch 9 and spaced from the walls of the stack. These walls have greater thicknesses at their bottoms whereby to surround a water drum 13 in each 85 wall in the immediate vicinity of the grates 14 which extend between the walls of the kiln and in the other direction to the walls of the furnace, and divide the space between the furnace walls into ash pits, 15, 90 separated by a grate-bridge 16, and a single fuel and fire zone 17. As shown, the furnace has a fuel door 18 and an ash door 19 at each end.

Supported on the furnace walls over the fire zone is the furnace top 20, whose sides converge upwardly so that the lime rock may move downwardly from the stack on each side of the furnace, and this furnace top is of sufficient size to surround a centrally located water drum 21.

At intervals throughout the lengths of the side walls of the furnace walls are the fire holes 22 which place the fire zone in direct communication with the stack and in these walls on each side of each fire hole and partly exposed to the fire zone are the water-tubes 23 connecting the drums 13 with the drum 21. By preference each of these water tubes includes an expansion joint 24. 110

Each of the drums projects through the kiln walls and each is provided, at at least one end with a man hole 25 for purposes of repair and cleaning.

5 Outside the kiln structure I provide a steam dome 26 which connects with the drum 21 by means of a pipe 27, including an expansion joint 28, and said steam dome connects with the drums 13 by means of 10 pipes 29, each of which includes an expansion joint 30.

Leading into each drum 13 is a water feed pipe 31 connected at or near one end and leading away from each drum, at or 15 near their other ends, is a blow-off pipe 32.

Extending through the walls of the kiln in line with the furnace are the poke holes 33, each of which has a suitable door 34, and in the kiln walls at right angles to the 20 walls having the poke holes 33 are the poke holes 35, having closures 36, in planes above the poke holes 33.

By the construction shown and as just described, it is apparent that I have a stack 25 kiln having a built in furnace within the stack and arranged to have a fire zone in direct communication with the stack, so that when in use the lime rock will surround the top and both sides of the furnace.

30 It is further apparent that the material, any of the known ceramics, entering into the furnace proper is uniformly protected against heat by water so distributed as to place in the various parts of the furnace a 35 body or volume of water proportionate with the dimensions of the furnace parts. In other words, the base of the furnace at each side, where the burned lime stands, I place the drums 13 which contain bodies of water 40 sufficient to consume enough of the heat at this point to relieve the furnace of heat beyond a degree which it is designed to successfully withstand.

In the side walls of the furnace, through 45 which there are openings formed to place the fire zone in direct communication with the stack, I place the relatively small tubes 23, one tube being on each side of each opening, and embedded in the wall, with a small 50 area exposed to the fire zone. These side walls being relatively thin prohibit the use of large tubes containing large bodies of water, hence the partial exposure of the tubes to the fire to cause increased water 55 circulation in the tubes and thus protect these thin walls against successive heat by a relatively small but rapidly circulated body of water instead of a larger, slowly circulated body of water as in the drums. 60 These tubes in addition to protecting the side walls from deterioration by heat, also

act as a reinforcement for the same, which is made necessary by the thinness of the wall and the number of fire openings therein.

In the top of the furnace, which occupies 65 a position in about the center of the calcining zone of the stack, where the furnace is exposed to the greatest heat, I place the drum 21, which is of a size to contain a much larger body of water than the other 70 bodies referred to, whereby to absorb sufficient of the heat to protect the upper furnace body.

Having thus described my invention, what I claim as new therein and desire to secure 75 by Letters Patent of the United States therefor, is:

1. A lime kiln comprising an internal furnace constructed of ceramic material, said furnace being provided with a fuel opening, 80 grate bars, ash pit, and whose side walls are spaced apart from the walls of the kiln and provided with a series of fire holes extending throughout their length, a drum located on each side of the furnace adjacent the 85 grate bars and partially in the heat zone, a drum of greater capacity than either of said drums located in the furnace above the combustion chamber, a series of tubes connecting the upper drum and the lower drums, 90 said tubes arranged adjacent to the fire openings and serve to protect the side walls from deterioration by heat and acting as a reinforcement for the same.

2. A lime kiln comprising an internal furnace constructed of ceramic material, the walls thereof being provided with a series of openings leading from the fire zone, a horizontally disposed drum located below the grate bars and adjacent thereto in each 100 side wall of the furnace, a drum of greater capacity than either of the first mentioned drums horizontally disposed in the arch of the furnace, a series of vertical tubes connecting the lower drums with the upper 105 drum, said vertical tubes being partially exposed to the heat of the combustion chamber, said drums protecting the furnace adjacent the grate bars from the excessive heat and the vertical tubes likewise protecting the 110 side walls of the furnace from excessive heat and also acting as a reinforcement for the side walls, and a steam drum located on the outside of the kiln and connected with said drums.

In testimony whereof, I have signed my name to this specification, in presence of two subscribing witnesses.

PHILIP J. DAUERNHEIM.
